US00D945448S

(12) **United States Design Patent** (10) **Patent No.:** **US D945,448 S**
Chaudhri et al. (45) **Date of Patent:** **** Mar. 8, 2022**

(54) **DISPLAY SCREEN OR PORTION THEREOF WITH GRAPHICAL USER INTERFACE**

(71) Applicant: **Apple Inc.**, Cupertino, CA (US)

(72) Inventors: **Imran Chaudhri**, San Francisco, CA (US); **Alan C. Dye**, San Francisco, CA (US); **Jonathan P. Ive**, San Francisco, CA (US); **Christopher Wilson**, San Francisco, CA (US); **Eric Lance Wilson**, San Jose, CA (US)

(73) Assignee: **Apple Inc.**, Cupertino, CA (US)

(**) Term: **15 Years**

(21) Appl. No.: **29/765,703**

(22) Filed: **Jan. 11, 2021**

Related U.S. Application Data

(63) Continuation of application No. 29/705,000, filed on Sep. 9, 2019, now Pat. No. Des. 908,715, which is a continuation of application No. 29/641,878, filed on Mar. 26, 2018, now Pat. No. Des. 859,431, which is a continuation of application No. 29/575,595, filed on Aug. 26, 2016, now Pat. No. Des. 813,891, which is a continuation of application No. 29/501,173, filed on Sep. 2, 2014, now Pat. No. Des. 765,114.

CLAIM

The ornamental design for a display screen or portion thereof with graphical user interface, as shown and described.

DESCRIPTION

The FIGURE is a front view of a display screen or portion thereof with graphical user interface showing the claimed design.

The outermost broken lines in the FIGURE show a display screen or portion thereof, and form no part of the claimed design. The other broken lines in the FIGURE show portions of the graphical user interface that form no part of the claimed design.

1 Claim, 1 Drawing Sheet
